(57) **CLAIM**

The ornamental design for an elastic housing for infusion device, as shown and described.

DESCRIPTION

FIG. 1 is a side elevational view of an elastic housing for an infusion device;

FIG. 2 is a first end elevational view thereof; and,

FIG. 3 is a second end elevational view thereof.

The broken line showing of the environment is for illustration purposes only and forms no part of the claimed design. The broken lines which define the boundaries of the claimed design form no part thereof.
